PHOTOGRAPHIC SLIDE VIEWER

Clarence Lee Folden, Downers Grove, Ill., assignor to
Sears, Roebuck and Co., Chicago, Ill., a corporation
of New York

Application May 29, 1956, Serial No. 41,694

Term of patent 14 years

(Cl. D61—1)

Fig. 1

Fig. 2

Fig. 1 is a front perspective view of a photographic slide viewer embodying my new design, and
Fig. 2 is a side elevation of same.

The dominant features of my design reside in the portions shown in full lines.

The side opposite that seen in Fig. 2 is similar to the one shown therein, and the back and bottom are plain.

I claim:

The ornamental design for a photographic slide viewer, as shown and described.
